G. H. WOODHOUSE,
MEANS FOR PREHEATING VOLATILE FUEL,
APPLICATION FILED SEPT. 5, 1919.

1,413,090.

Patented Apr. 18, 1922.

FIG. 1.

FIG. 2.

Inventor
George H. Woodhouse
By his Attorney
Marion Fenwick Lawrence,

UNITED STATES PATENT OFFICE.

GEORGE H. WOODHOUSE, OF SEATTLE, WASHINGTON.

MEANS FOR PREHEATING VOLATILE FUEL.

1,413,090.

Specification of Letters Patent. Patented Apr. 18, 1922.

Application filed September 5, 1919. Serial No. 321,837.

To all whom it may concern:

Be it known that I, GEORGE H. WOODHOUSE, a citizen of the United States, residing at 108 W. Mercer St., Seattle, in the 5 county of King and State of Washington, have invented certain new and useful Improvements in Means for Preheating Volatile Fuel; and I do hereby declare the following to be a full, clear, and exact description of the invention, such as will enable others skilled in the art to which it appertains to make and use the same.

This invention relates to means and method for preheating fuel gases for use in 15 internal combustion engines, and particularly for so preheating the gases by contact with the heated body of the explosion chamber, and so utilizing the heat created by the explosions, to preheat the gases which are 20 successively used to create the explosions, before such gases enter the explosion chamber.

The purposes of the invention are to provide means for so preheating the fuel gases 25 for use in internal combustion engines, that when such heated gases enter the explosion chamber they will be in a heated and volatile condition and in condition to produce the highest propelling force when exploded by 30 the ordinary spark supplied; and the further purpose to utilize for such preheating, the heated part of the explosion chamber.

A further purpose of my invention is to provide a chambered cylinder head for the 35 explosion chamber or cylinder, and to pass the gas mixture through the chambers of such head whereby they are properly heated before they enter the cylinder.

My drawings further illustrate my invention, as follows:

Figure 1, represents a cross section side view of the device.

Figure 2, represents a sectional plan view, taken on line A. A. on Fig. 1.

Like numerals on the figures represent like parts.

Numeral 1, represents the outer side walls of my heating cylinder head, with a floor 7 supported by and connected upon the top of 50 any ordinary explosion cylinder 2 of an internal combustion engine, by means of ordinary bolts and nuts 3, the bolts passing through holes 4 in the side walls of the head 1.

An intake supply pipe 5 brings the supply 55 of gas mixture from any ordinary carbureter

and this is drawn into the chamber 6 of the head by the suction of the piston action in the cylinder 2 as usual. Near one edge of the chamber 6 is placed U shaped baffle wall 60 9, the points thereof 9^a and 9^b turned toward the outer walls 1 of the head, with spaces between the said points and the wall 1 sufficient for the gases to pass between and enter the cylinder 2 through valve 10 and port 65 10^a in lower shell 7 of the head, the valve being provided with a stem 11 and spring 12 with stop cap 13 above the top 8 of the head.

In the said lower shell 7 is also provided 70 an exhaust port 14 for the escape of the burned gases through a stop valve 15 with stem 16, which control spring and cap 17 and 16', the valve being operated by an ordinary lever 18 on post 19 and connecting rod 75 20 from the ordinary cam shaft connected to the moving parts of the engine as in ordinary gas engines, the waste matter passing out through connecting part 21 forming a wall in the chamber 6 and adjoining pipe 22. 80

In operation the chambered head 1 is heated by the first explosions of gas in the cylinder 2, and thereafter as the gas mixture is drawn into the chamber 6 it is heated and expanded in the hot chamber, and brought 85 into a condition to produce a much greater force when exploded than under the usual manner of being introduced cold, and the engine equipped with this apparatus will run with less fuel and produce more power. 90

While I have described the objects and construction of this apparatus as for gases, yet I do not limit the use and claims and objects thereby, as the apparatus is of equal 95 value in the use of low grade oils and liquid fuels, and by the use of the apparatus I am able to utilize such other liquid fuels by engines equipped with my apparatus, and get results as good as from the use of more expensive fluids and gases when used on an 100 engine without my apparatus, as by my preheating system the low grade liquids are made gaseous and combustible in an explosive cylinder.

I claim:

1. The combination in an internal combustion engine, of a cylinder, a chambered head therefor provided with fuel inlet and exhaust valves in its inner wall, said head being divided by a single partition into two 110 unequal chambers of the full height of said chambered head, both communicating with

the combustion space of the cylinder, the larger one by means of the fuel inlet valve and the other by means of the exhaust valve, said chambers having radial inlet and outlet ports respectively, adjacent each other in the side wall of said head, said inlet port being arranged to direct the incoming fuel obliquely against the partition wall dividing said chambers.

- 10 2. The combination in an internal combustion engine, of a cylinder, a chambered head therefor provided with fuel inlet and exhaust valves in its inner wall, said head having two chambers, both in communication with the combustion space of the cylinder, one by means of the fuel inlet valve and the other by means of the exhaust valve, said chambers having radial inlet and outlet ports respectively, adjacent each other in the side wall of said head, a vertical baffle plate partially surrounding the valved inlet port, there being a narrow passage between said baffle plate and the partition separating said chambers.
- 15 20 25 3. The combination in an internal combus-

tion engine, of a cylinder, a chambered head therefor, provided with fuel inlet and exhaust valves in its inner wall, said valves being spaced equally from the center of said head on the same diametrical line, said head having two chambers both communicating with the combustion space of the cylinder, one by means of the fuel inlet valve and the other by means of the exhaust valve, said chambers having radial inlet and outlet ports, respectively, adjacent each other in the side wall of said head, a curved partition separating the chambers, said partition partially surrounding the exhaust valve, and being disposed in the path of the incoming fuel, and a curved baffle wall partially surrounding the fuel inlet valve, there being a narrow space between the baffle and the said curved partition, the fuel inlet port being so located as to direct the incoming fuel against the partition wall and through the space between said wall and baffle.

In testimony whereof I affix my signature.

GEORGE H. WOODHOUSE.
